UNITED STATES PATENT OFFICE.

THOMAS M. LAVELLE, OF POTTSVILLE, PENNSYLVANIA.

BUFFER FOR DOORS.

1,073,253.

Specification of Letters Patent. Patented Sept. 16, 1913.

Application filed January 23, 1913. Serial No. 743,794.

To all whom it may concern:

Be it known that I, THOMAS M. LAVELLE, a citizen of the United States, residing at Pottsville, in the county of Schuylkill and State of Pennsylvania, have invented certain new and useful Improvements in Buffers for Doors; and I do declare the following to be a full, clear, and exact description of the invention, such as will enable others skilled in the art to which it appertains to make and use the same.

This invention relates to improvements in buffers for doors and particularly to buffers for the doors of automobiles, carriages, boats and the like.

One object of the invention is to provide a buffer of this character having means whereby the same may be adjusted without removal from the door when the projecting portion of the buffer has been flattened or worn down, thus keeping the door tight and preventing the same from rattling.

Another object is to provide a device of this character which will be simple, strong, durable and inexpensive in construction, efficient and reliable in operation, and in which the elastic plug thereof may be readily removed and renewed when entirely worn out.

With these and other objects in view, the invention consists of certain novel features of construction, and the combination and arrangement of parts as will be more fully described and claimed.

In the accompanying drawings: Figure 1 is a horizontal sectional view of one of the jambs and the adjacent edge of an automobile door showing my improved buffer applied thereto and in section; Fig. 2 is a front view of a portion of the door jamb and of the buffer; Fig. 3 is a vertical sectional view of the jamb and buffer taken on the line 3—3 of Fig. 1; Fig. 4 is a similar view showing the manner in which the buffer blocks are engaged with and removed from their casings; Fig. 5 is a detail perspective view of the attaching plates for the buffer blocks; Fig. 6 is a view similar to Fig. 3 showing a slightly modified form of the invention.

By reference to the accompanying cut it will be seen that my improved buffer comprises a casing 1, which may be of any suitable shape to conform to the configuration or shape of the door jamb to which the same is to be applied, said casing being

mortised into the jamb and having formed thereon suitable attaching flanges 2 provided with screw holes for receiving the fastening screws whereby the casing is secured in position on the door jamb. In the outer side of the main or body portion of the casing is formed a recess 3 and in its inner side a recess 4, said recesses being connected by a centrally disposed passage 5 as shown.

Slidably and adjustably engaged with the recess 3 in the body of the casing is the buffer block 6 which is preferably formed of rubber but which may be formed of any suitable resilient or elastic material which will form a cushion against which the door is closed and which will hold the door against rattling. The buffer block 6 is adjustably held in position in the recess 3 of the casing by a bolt or stud 7 which has a screw threaded engagement with the passage 5 in the casing as shown. The inner end of the stud 7 is engaged with a circular recess 8 formed in the inner side of the buffer block 6 and in the stud 7 near its inner end and adjacent to the inner side of the block 6 is formed an annular recess 9 with which are engaged the forked or bifurcated ends of block and stud attaching plates 10. The forked or bifurcated ends of the plates are engaged with the recess 9 of the stud from opposite directions and overlap each other as shown. The outer ends of the plates 10 are bent outwardly at right angles and then inwardly to form right angular block gripping lugs 11 which engage notches 12 formed in the ends of the block as clearly indicated in Figs. 3, 4 and 5 of the drawings. By forming the plates 10 and engaging the same with the recess 9 in the stud 7 the latter is swiveled to the block 6 and when the gripping lugs 11 of the plates are engaged with the notches 12 in the block and the latter inserted in the recess 3 of the casing, said plates will be held in position for connecting the stud or bolt with the block.

The block 6 is of sufficient width or thickness to project to a suitable distance beyond the outer side of the casing to prevent the door from coming into engagement with the jamb and by means of the stud 7 it will be seen that when the projecting portion of the block becomes flattened or worn off from the continued closing of the door the bolt or stud may be turned in the proper direction to further project the block and to

thereby hold the door against rattling which would occur when the projecting end of the block has worn off or become flattened. This adjustment also obviates the necessity of removing the casing and securing therein a new buffer block as is necessary in the ordinary form of door buffers now in use.

After the bolt or stud has been adjusted to bring the buffer block to the desired position the bolt is locked for holding the block in this position by a jamb nut 13 which is screwed up on the bolt and against the inner wall of the recess 4 in the inner side of the casing as shown. The outer end of the stud projects a slight distance beyond the inner side of the door jamb and is provided with a reduced squared end 14 to receive a key or wrench for turning the bolt, said wrench being also preferably adapted for engaging and turning the jamb nut 13.

By attaching the buffer block 6 to the end of the bolt or stud 7 as herein shown and described, it will be seen that when the block has become worn to such an extent as to prevent further adjustment, it is simply necessary to screw the bolt outwardly to a sufficient extent to permit the inner end of the block and the fastening plates to clear the outer end of the recess 3, whereupon the plates may be slipped outwardly in opposite directions to a sufficient extent for disengaging the bifurcated ends thereof from the recess 9 in the bolt or stud whereupon the block may be disengaged from the end 35 of the bolt and a new block placed in position thereon and fastened by the plates in the manner described.

In the last figure of the drawings is shown a sectional view of a slightly modified form 40 of the buffer wherein in addition to the adjusting stud or bolt, I also provide short coiled springs 15 for forcing the block outwardly when the bolt is turned in the proper direction, said springs being preferably disposed in short sockets 16 formed in the main or body portion of the casing on each side of the threaded passage therein, and having their outer ends engaged with the outer block attaching plate 10 as shown.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. A buffer for doors comprising a casing adapted to be secured in the frame of the door and having therein a block receiv-

ing with said recess, a buffer block having a sliding engagement with the block receiving recess of the casing and a block adjusting stud having a threaded engagement with the passage in said casing, and a swiveled connection with said buffer block whereby the latter is adjusted to project the outer end thereof from the casing.

2. A buffer for doors comprising a casing adapted to be secured in the door jamb and having therein block and nut receiving recesses, and a threaded passage connecting said recesses, a buffer block slidably and adjustably engaged with said block receiving recess, an adjusting bolt having a threaded engagement with the passage in said casing, and a detachable swiveled connection with said block, and a jam nut adapted to be screwed onto said bolt and into engagement with the inner wall of said nut receiving recess whereby the bolt is locked for holding the buffer block in its adjusted position.

3. A buffer for doors comprising a casing adapted to be secured in the door jamb and having therein a block receiving recess and a threaded passage communicating therewith, a resilient buffer block having in its inner side a circular recess and in its ends transverse notches, an adjusting bolt adapted to be screwed into said threaded passage and having its end engaged with the circular recess in the buffer block and provided with an annular recess, bolt and block attaching plates having bifurcated inner ends adapted to be overlapped and engaged with the annular recess in the end of said bolt, right angular gripping lugs on the outer ends of said plates to engage the transverse notches in the ends of the buffer block whereby the latter is fastened to the bolt and the bolt swiveled to the block to permit the latter to be projected when said bolt is screwed inwardly in the threaded passage of the casing.

4. A buffer for doors comprising a casing adapted to be secured in the door jamb and having therein a block receiving recess and a threaded passage communicating therewith, a resilient buffer block having in its inner side a circular recess and in its ends transverse notches, an adjusting bolt adapted to be screwed into said threaded passage and having its end engaged with the circular recess in the buffer block and provided with an annular recess, bolt and block attaching plates having bifurcated inner ends adapted to be overlapped and engaged with the annular recess in the end of said bolt, right angular gripping lugs on the outer ends of said plates to engage the transverse notches in the ends of the buffer block whereby the latter is fastened to the bolt and said bolt swiveled to the block to permit the latter to be projected when said bolt is 130

screwed inwardly in the threaded passage of the casing, and springs arranged in the casing and engaged with the bolt attaching plates and inner end of the buffer block 5 whereby the latter is forced outwardly when the adjusting bolt thereof is turned in the proper direction.

In testimony whereof I have hereunto set my hand in presence of two subscribing witnesses.

THOMAS M. LAVELLE.
